UNITED STATES PATENT OFFICE.

AUSTIN W. HOOVER AND ROBERT WINTER, JR., OF IRWIN, PENNSYLVANIA, ASSIGNEES TO DUAL-TONE PHONOGRAPH & MANUFACTURING COMPANY, OF MANOR BOROUGH, PENNSYLVANIA, A CORPORATION OF PENNSYLVANIA.

PHONOGRAPH.

Application filed November 12, 1919. Serial No. 337,605.

To all whom it may concern:

Be it known that we, AUSTIN W. HOOVER and ROBERT WINTER, Jr., citizens of the United States, and residents of Irwin, in the 5 county of Westmoreland and State of Pennsylvania, have made a new and useful Improvement in Phonographs, of which the following is a specification.

Our invention relates to sound reproducing devices and consists of phonograph parts adapted to develop and deliver sound waves from the usual sound records more efficiently and with better tonal results than similar parts previously used.

15 One of the defects of present phonographs is their inability to reproduce all of the sounds recorded and their faulty reproduction and amplification of the tones of the sounds which they do yield. The object of 20 our invention is to eliminate these defects and we attain our object by manufacturing phonograph reproducing and developing parts of a material hitherto unused for that purpose and by providing otherwise improved passages thru which the sound waves 25 travel to the atmosphere.

In the accompanying drawings, Figure 1 is a partial section and elevation of the main parts of a phonograph; Fig. 2 is a plan and 30 section of the same parts and Fig. 3 is a vertical section on line 3—3 of Fig. 1.

35 Partition 1 of the phonograph box or cabinet supports the rotating table 2 for record 3 and supports a collar 4 for base 5 of the tone arm. The entrance end of the sound chamber 6 is also secured to partition 1 and aligned with the end of collar 4 and tone arm base 5. A sound box 7 is mounted on the vertically pivoted end 8 of the tone arm and 40 is provided with a needle 9 of the usual type.

The tone arm begins with the usual tubular passage as indicated at 8 but a short distance from the sound box 7 the passage divides and forms two passages 10 and 11, 45 which diverge from each other and are pivotally telescoped into passages 12 and 13 respectively, which form continuations of passages 10 and 11, expand thruout their length and, at the rear of the arm, unite in base 5 opening into sound chamber 6.

Each sound wave created at the sound box

travels thru passage 8 and, at the divisional point, generates duplicate waves which travel thru both passages 10—12 and 11—13 and at the end of these passages unite in a 55 single wave to proceed thru base 5 and collar 4 to sound chamber 6. The end of base 5 telescopes into collar 4 and is supported upon ball bearings 14 and is secured against unintentional removal from its seat by a 60 screw 15 attached to a bridge 16 in collar 4. This support gives the divided arm pivotal movement about the axis of its base.

The use of a double tone arm gives remarkable results in the tonal qualities of the 65 sounds reproduced. By substituting our arm for a single arm we have obtained from the same record and with the same sound box, not only better tones for all sounds, but even some sounds not previously audible. 70

While we have illustrated a tone arm having but two separate passages it will be apparent that the arm may be divided into any number of passages and fall within the spirit of this invention. 75

Those parts of sound box 7 which are usually made of brass or other metal, we construct of a phenolic condensation product, some familiar examples of which are marketed under the trade names "bakelite," 80 "rodmanol," "condensite," etc. The tone arm is preferably made of the same substance altho, even when constructed of wood or such metals as are utilized in the ordinary tone arms, the greatly improved results mentioned are obtained.

The tone chamber 6 is also formed from a phenolic condensation product. This material is easily molded, or cast in the peculiar shapes adapted for phonograph parts 90 and possesses unusual tonal qualities. When solidified it forms a hard, smooth surface which resonantly conveys the reproduced waves without affecting their purity by adding metallic and woody sounds such as accompany the efforts of the talking machines now in use. 95

We claim:

1. In a tone arm, an entrance passage which divides and forms separated, diverging passages, separated, substantially parallel passages which unite in a common exit 100

passage, and a pivotal, telescoping connection between said diverging passages and said separated passages.

2. In a phonograph, a sound chamber, a horizontally swinging, two passage tone arm connecting with said sound chamber, a sound box and vertically swinging means connect-

ing the interior of said sound box with the passages of said tone arm.

In testimony whereof, we have hereunto 10
subscribed our names, this 6th day of November, 1919.

AUSTIN W. HOOVER.
ROBERT WINTER, JR.
